UNITED STATES PATENT OFFICE.

WILLIAM H. SAYRE, OF GLEN RIDGE, NEW JERSEY.

RABBLE-BLADE.

1,340,916.

Specification of Letters Patent.

Patented May 25, 1920.

Application filed July 27, 1918. Serial No. 246,982.

To all whom it may concern:

Be it known that I, WILLIAM H. SAYRE, a citizen of the United States, residing at Glen Ridge, in the county of Essex and State of

5 New Jersey, have invented certain new and useful Improvements in Rabble-Blades, of which the following is a specification, reference being had therein to the accompanying drawing.

10 This invention relates to wear resistant materials, and it is particularly applicable to "rabble" blades for mechanical furnaces used in the roasting of ores or other similar materials.

15 One form of mechanical furnace used for the foregoing purposes comprises a cylindrical casing within which revolves a central shaft, from which shaft extend radial arms which are usually disposed in pairs, 20 the members of which are 180° apart and which revolve with the shaft in one of the compartments into which the furnace is divided by horizontal partitions. To said arms are secured rabble blades, so-called, 25 whose office is to move the material to be treated in the furnace. Owing to the nature of the said material and process, the rabble blades are very short-lived, their bodies, and particularly their sides, being quickly worn 30 away by the abrading contact of the pieces of the material being treated. As a result of this wearing away of the rabble blades, the said material accumulates, and it is necessary to "bar" or separate the pieces 35 thereof, during which process poisonous gases may be given off.

With these defects in view, objects of the invention are to provide a rabble blade which shall be highly wear-resistant and 40 which will be efficient and economical in construction and operation. These and other objects of the invention will in part be obvious and in part be more fully explained in the following description.

45 In the accompanying drawings, which are referred to herein and form part hereof, are illustrated several embodiments of the invention, the same serving in connection with the description herein to explain the principles of the invention and to set forth its 50 advantages.

Of the drawings:

Figure 1 is a side view of a rabble blade constructed in accordance with certain features of the invention;

Fig. 2 is a similar view showing a different arrangement of the hard mineral elements by means of which the blade is made wear-resistant;

Fig. 3 is an end or edge view, partly in section, of a rabble blade made in accordance with one feature of the invention;

Fig. 4 is a side view, partly in section, of a rabble blade made in accordance with one feature of the invention and showing the hard mineral elements in the side portion of the blade arranged in horizontal rows; and

Fig. 5 is a view similar to Figs. 1 and 2, but showing the said mineral elements arranged in intersecting diagonal rows.

A rabble blade constructed in accordance with the invention comprises a body portion, and wear-resistant elements disposed in the side thereof so as to protect the said side face from wear, while at the same time not unduly weakening the said body.

In the preferred embodiment of the invention, the said wear-resistant elements are composed of hard mineral, as alundum, and are disposed in spaced-apart horizontal rows.

Referring in detail to the drawings, there is illustrated in Fig. 2 an embodiment of the invention comprising a body 7 of a rabble blade such as is employed in a mechanical furnace used, for example, in smelting copper or manufacturing sulfuric or other acids. As such furnace and its parts are well known in the art, it will be unnecessary to describe them. As heretofore stated, a rabble blade is secured at its upper portion 8 to a revolving arm of the machine by which it is moved through the material being treated. A common form of rabble blade is made of metal, as cast iron, and it will readily be seen that because of the nature of the materials being treated and of the process of treating the same, the wear on the rabble blade is very severe and the life of the blade consequently is very short.

To render the blade more wear-resistant and thus prolong its life, while at the same time avoiding the other consequent defects heretofore noted, and in accordance with one feature of the invention, elements 9, 105 which are of a highly wear-resistant nature, are disposed throughout the opposite side faces of the blade in such fashion as to protect the said sides from the abrading contacts of the pieces of material being treated.

Preferably, these elements are composed of hard mineral substances, such as artificial corundum, known as "alundum," and are made of suitable proportions. It will be noted that these elements may be disposed throughout the body of the blade during the casting process, the material composing the elements being of such nature as not to be injuriously affected by the heat of the molten metal. Preferably, also, the elements will be of such size as to extend through the body of the blade and project on both sides.

It is desirable, however, not to weaken the structure of the blade, and therefore in the best embodiment of the invention, the elements are disposed in the side faces of the blade suitably spaced apart. Several examples of this spacing apart of the elements are shown in the drawings. In Fig. 2, for example, the elements are disposed irregularly, but yet in a manner to protect the sides of the blade from wear. In the preferred embodiment illustrated in Fig. 4 the elements are disposed in horizontal rows at spaced intervals, and in Figs. 1 and 5 other formations are illustrated.

It will be seen that a rabble blade constructed in accordance with the invention as heretofore described will carry out the objects of the invention as enumerated, as well as possess other advantages which will be apparent to those skilled in the art.

While I have shown and described my invention as applied to a rabble blade for use in ore roasting furnaces, it is manifest that the invention is not confined to such special application, but may be employed also in connection with other forms of stirring or agitating devices to prevent wear thereon by the abrasion of the material acted on, such for instance as paddle blades or mixing blades for use in pug mills, or other forms of mixing or agitating blades for acting on other materials.

The invention in its broader aspects is not limited to the precise construction or constructions shown and described, as many changes may be made in the details thereof without departing from the main principles of the invention or sacrificing its chief advantages.

I claim:

1. A member for agitating or stirring material, said member having a body portion adapted to be moved through the material and agitate or stir the same, said body portion having wear-resistant elements disposed in the side face thereof to protect the same from wear by the abrasion of the material thereon.

2. A rabble blade adapted to be moved through material to agitate the same, and having wear-resistant elements disposed in the side face thereof to prevent the blade

from wear by the abrasion of the material 65 thereon.

3. A member for agitating or stirring material, said member having a metal blade portion adapted to be moved through the material and agitate or stir the same, said 70 blade portion having hard wear-resistant elements disposed in the side face thereof to protect the blade from wear by the abrasion of the material thereon.

4. A member for agitating or stirring 75 material, said member having a metal blade portion adapted to be moved through the material and agitate or stir the same, said 80 blade portion having alundum wear-resistant elements disposed in the side face thereof to protect the metal from wear by the abrasion of the material thereon.

5. A member for agitating or stirring material, said member having a blade portion 85 adapted to be moved through the material and agitate or stir the same, said blade portion having hard wear-resistant elements disposed in spaced apart groups in the side face thereof to protect the blade from wear by the abrasion of the material 90 thereon.

6. A member for agitating or stirring material, said member having a blade portion 95 adapted to be moved through the material and agitate or stir the same, said 100 blade portion having hard wear-resistant elements disposed in spaced apart rows in the side face thereof to protect the blade from wear by the abrasion of the material thereon.

7. A member for agitating or stirring material, said member having a blade portion 105 adapted to be moved through the material and agitate or stir the same, said 110 blade portion having hard wear-resistant elements disposed in spaced apart horizontal rows in the side face thereof to protect the blade from wear by the abrasion of the material 115 thereon.

8. A member for agitating or stirring 110 material, said member having a body portion adapted to be moved through the material and agitate or stir the same, said body portion having wear-resistant elements disposed in both side faces thereof to protect 115 the same from wear by the abrasion of the material thereon.

9. A rabble blade adapted to be moved through material to agitate the same, said 120 blade having wear-resistant elements disposed in both side faces thereof to protect the said faces from wear by the abrasion of the material thereon.

10. A member for agitating or stirring material, said member having a blade portion 125 adapted to be moved through the material and agitate or stir the same, said blade portion having wear-resistant ele-

ments disposed at intervals in the side face thereof to protect the same from wear by the abrasion of the material thereon.

11. A member for agitating or stirring material, said member having a flat metal blade adapted to be moved facewise through the material and agitate or stir the same,

said blade having hard wear-resistant elements disposed in the side face thereof to protect the metal from wear by the abrasion 10 of the material thereon.

In testimony whereof I have affixed my signature hereto.

WILLIAM H. SAYRE.
